MOBILE ORCHARD HEATING APPARATUS

Ray H. Taber, Chula Vista, Calif.

Application October 28, 1937, Serial No. 171,417

12 Claims.

(Cl. 47-2)

My invention relates to a mobile orchard heating apparatus, and the objects of my invention are:

First, to provide a mobile heating apparatus;

5 Second, to provide a mobile heating apparatus which may be used in orchards susceptible to injury by frosts to prevent or to minimize such injury;

10 Third, to provide an apparatus of this class which may be used in place of the large number of stationary orchard heaters normally used in the citrus growing districts to prevent injury to citrus trees by frost;

15 Fourth, to provide an apparatus of this class by which heat may be readily conveyed or directed to any one place in an orchard by means of forced draft;

20 Fifth, to provide a mobile heater by which the heat generated therein is directed downwardly against and along the surface of the ground; and

25 Sixth, to provide on the whole a novelly constructed mobile orchard heating apparatus which is relatively durable, efficient in its function, and which will not readily deteriorate or get out of order in proportion to its function.

30 With these and other objects in view as will appear hereinafter, my invention consists of certain novel features of construction, combination, and arrangement of parts and portions as will be hereinafter described in detail and particularly set forth in the appended claims, reference being had to the accompanying drawings and to the characters of reference thereon which form a part of this application in which:

35 Figure 1 is a top or plan view of my mobile orchard heating apparatus; Fig. 2 is a side elevational view of the mobile orchard heating apparatus; Fig. 3 is a fragmentary sectional view taken along the line 3-3 of Fig. 1 and is on a

40 slightly enlarged scale over the Fig. 1; Fig. 4 is a sectional view taken along the line 4-4 of Fig. 3 and is of the same scale as Fig. 3; Fig. 5 is a sectional view taken along line 5-5 of Fig. 3 of the same scale as Fig. 3; Fig. 6 is a flow dia-

45 gram for this mobile orchard heating apparatus; Fig. 7 is a fragmentary transverse sectional view similar to Fig. 3 of a modified form of firebox and heat mixing and discharge chamber and is of the same scale as Fig. 3; Fig. 8 is a sectional

50 view taken along the line 8-8 of Fig. 7 and is of the same scale as Fig. 7; Fig. 9 is a sectional view taken along line 9-9 of Fig. 7 and is of the same scale as Fig. 7; and Fig. 10 is a fragmentary sectional view taken along line 10-10 of Fig. 9

55 of the same scale as Fig. 9.

Similar characters of reference refer to similar parts and portions throughout the several views of the drawings:

The frame 1, the front castor wheel 2, the rear wheels 3 and 4, oil tank 5, internal combustion engine 6, air compressor 7, compressed air storage tank 8, gas generating vaporizer 9, fuel oil preheater 10, fuel oil burner 11, centrifugal fan blower 12, firebox 13, and heat mixing and discharge chamber 14 constitute the principal parts 10 and portions of my novel mobile orchard heating apparatus.

The frame 1 is supported at its front end by the castor wheel 2. This castor wheel 2 is carried between the fork member 2a, the upper 15 end of which member 2a is journaled within the support member 1a at the front end of the frame 1. This front wheel 2 is used for steering this mobile orchard heating apparatus. The rear end of this frame 1 is secured to the underslung 20 axle 3a which axle extends between the rear wheels 3 and 4. Transversely positioned across the front end of the frame member 1, as seen best in Fig. 1 and to some extent in Fig. 2 of the drawings, are the internal combustion engine 6 25 and the air compressor 7. Fuel to drive this internal combustion engine 6 is supplied from the tank 6a through the conduit 6g. The air compressor 7 is driven by this internal combustion engine 6 through the flexible coupling member 6f. The centrifugal fan blower 12 is also driven from this internal combustion engine 6 by means of the pulley member 6d which is secured to the shaft 6e, which shaft is driven by the internal combustion engine 6, and by the belt 12c which 35 belt extends between the pulley 6b and another pulley 12b positioned upon a shaft 12a for the blower fan of this centrifugal fan blower 12. To the end of the shaft 6e driven by the internal combustion engine 6 is secured a cooling fan 6c. 40 This fan 6c not only serves to direct a draft of air over the block of the internal combustion engine 6 but also serves to create a draft through the radiator member 6b. This radiator member 6b is used in connection with the internal combustion engine 6. The compressor 7 exhausts 45 directly into tank 8 through pipe 1a.

Mounted upon the support 1b some distance above the frame 1 is the oil tank 5. Beneath this oil tank and centrally positioned between the 50 sides of the frame 1 is the centrifugal fan blower 12. This blower 12 discharges directly into the passageway 14a of the heat mixing and discharge chamber 14.

This passageway is directly above the firebox 55

13 as may be seen best in Figure 3 of the drawings. The firebox 13 is lined with a refractory material 13a. The fuel oil burner 11 is positioned within the firebox 13 as shown in Fig. 3 of the drawings. Positioned at the forward end and on the outside of the firebox 13 is the gas generating vaporizer 9. This vaporizer 9 communicates directly with the fuel oil burner 11. The fuel oil in tank 5 is under pressure of compressed air, the compressed air being conveyed from tank 8 through reducing valve 8b to tank 5 by means of a conduit 5a. Thus the oil in tank 5 flows by aid of gravity and pressure from the oil tank 5 through pipe 5b to preheater coils 10 which preheater coils are positioned as indicated in Figs. 1, 2, and 3 of the drawings, and which are removably positioned in recess 13c in the refractory lining 13a of the firebox 13. The fuel oil after passing through the preheater coils 10 flows through pipe 10a to the gas generator 9 where it is mixed with compressed air. Compressed air is fed to this generator 9 through reducing valve 8a from compressed air tank 8 by means of the conduit 8c, first being preheated by passing through coils 8d removably positioned in recess 13c. The mixture of air and oil then passes directly from this gas generator to a fuel oil burner positioned in the firebox 13 as shown in Fig. 3 of the drawings. Figure 6 of the drawings shows the flow diagram for both the fuel oil and the compressed air.

The heat mixing and discharge chamber member 14 is supported upon the rear end of the frame 1 as shown best in Figs. 1 and 2 of the drawings. The forward end of this chamber 14 connects with the discharge of the blower 12, and the rear or discharge end 14h of the chamber 14 is supported by the rear end of the frame 1. The direction of flow of air from the centrifugal fan blower 12 is from the forward end of this chamber 14 to the rearward discharge end 14h. So also for the gases discharged from the firebox 13; but the gases from the firebox 13 do not mix with the air from the blower 12 until the two have passed the point 14g as shown in Fig. 3 of the drawings. The cross section shape of this chamber 14 is substantially rectangular at any plane taken transversely through the same between the intake 14a and the discharge 14h, but the cross sectional area grows progressively larger as the plane of the cross section is moved toward the discharge end 14h. This is indicated best in Fig. 1 of the drawings. Between the points 14f and 14g, this chamber 14 is divided into a plurality of passageways by the vertically standing partitions 14b. In Fig. 4 of the drawings, the passageway within the member 14 is shown divided into nine of these conduits 14c and 14d. The conduits 14d connect directly with the firebox 13, the hot gases discharged therefrom coming up through the opening 14e in the lower side of this chamber 14 and passing backwardly through the conduits 14d. This is indicated in Figs. 3 and 5 of the drawings. The air from the blower 12 passes along the passageway 14a and between the conduits 14d by passing through the conduits 14c. It should be noted that the drawings show five of these conduits 14c and four of the conduits 14d. Thus the hot gases from the firebox 13 and the air from the blower 12 do not mix until both have passed the end of their respective conduits 14c and 14d which is indicated at point 14g in Fig. 3 of the drawings. It should be noted in Fig. 3 of the drawings that the firebox 13 has an opening 13b 75 which permits a draft so that the gases from the

oil burner 11 may leave the firebox 13 and pass out into the conduit 14d. These partitions 14b serve a double purpose. First, they divide the chamber 14 into a plurality of conduits so that the hot gases from the firebox 13 and the air from the blower 12 are kept separate until they both reach the point 14g, which point is well to the rear of the openings 14e from the firebox 13 in the lower side of this mixing chamber 14. This prevents the air from the blower 12 from passing into the firebox 13 and blowing flame off the burner 11. This also induces a draft through the opening 13b in the firebox 13 that helps to draw the hot gases from the firebox 13 out into the conduits 14d. Secondly, these partitions 14b provide a greater heating surface for the hot gases from the firebox 13 so that the air from the blower 12 in scrubbing past these partitions 14b in passing through the conduit 14c will pick up considerable heat long before the point 14g is reached where the air and hot gases may mix. It should be noted from Figs. 2 and 3 of the drawings, that the forward end of the chamber 14 is elevated above the discharge end 14h and further that this discharge end 14h is but a very short distance above the surface of the ground so that the hot gases discharged from this chamber 14 will be directed downwardly onto and along the surface of the ground. The discharge end 14h is always open. A pair of deflector members 14t and 14r are positioned at the rear end of member 14 to deflect the gases as indicated by the arrows shown in Fig. 1 of the drawings. A pair of shutters 14i and 14j are positioned, one on each side of the chamber 14 near the rear end of said chamber. The shutter 14i is hinged at 14k and the shutter 14j is hinged at 14m. These shutters may be opened or closed at will, and when opened permit the hot gases being discharged to travel out transversely from each side of the chamber 14 due to deflectors 14t and 14r as well as from the rear end 14h thereof.

The operation of the preferred mobile orchard heating apparatus hereinbefore described is as follows:

The apparatus may be towed through an orchard by connecting a chain or cable with the eye 2c on the yoke 2b over the castor wheel 2. As the apparatus is towed, heat will be discharged from the rear end 14h of the chamber 14 in a downward direction against and along the ground so as to prevent the formation of frost. The heat may also be discharged laterally from each side of the discharge chamber 14 near the rear end thereof by opening the shutters 14i and 14j. Thus the heat may be discharged out along the surface of the ground underneath the trees to be protected as the apparatus is towed between the rows of trees, the fuel consumed in the firebox 13 furnishing the heat necessary therefor, and the blower 12 furnishing the draft necessary to discharge the heat from said discharge chamber 14.

In Figs. 7, 8, 9, and 10 is shown a modified form of this discharge chamber 14. The principal difference between the modified and preferred form is that in the modified form the firebox 15 is mounted on the top side of the discharge chamber 14 about midway between the front end of member 14 and the discharge end 14h, whereas in the preferred form the firebox is on the under side of this chamber 14 and towards the forward end of said chamber 14; also, in the modified form the direction of travel of the flame and gases from the burner 11 is counter to the direction of travel of air from blower 12 and gases from this firebox 75

15 through the discharge chamber 14, whereas in the preferred form the direction of travel of the flame and gases within firebox 13 is with the direction of travel of air and gases in the member 14. This is indicated by the arrows in Figs. 3 and 7 of the drawings. The discharge chamber 14 in the modified form has also the plurality of partitions 14b as indicated in Fig. 9 of the drawings. The gases exhausted from the firebox 15 pass through the conduits 14d and the air from the blower 12 enters the discharge chamber at 14a and passes through the conduits 14c. The air from the blower 12 and the gases from the firebox 15 do not mix until the same have passed 10 the ends of partitions 14b at the point 14g as indicated in Fig. 7 of the drawings. The gases from the firebox 15 pass through openings 14s in the upper surface of the discharge chamber 14 directly into the conduits 14d. These openings 15 are shown in Fig. 10 of the drawings. Air is admitted to the firebox 15 through 15b as shown in Fig. 7 of the drawings. This firebox 15 is also lined with a refractory material 15a as shown in Fig. 7 of the drawings, and the fuel oil preheater coils 10 and air preheater coils 8d are removably positioned in recess 15c in lining 15a as shown in Fig. 7 of the drawings. The member 14, in its modified form also has deflectors similar to 14t and 14r, and shutters similar to 14i and 14j.

30 The operation of the orchard heating apparatus with the modified form of firebox and discharge chamber is the same as for the preferred form.

Though I have shown and described a particular construction, combination, and arrangement of parts and portions and a certain modification thereof, I do not wish to be limited to this particular construction, combination and arrangement, nor to the modification, but desire to include in the scope of my invention, the construction, combination, and arrangement substantially as set forth in the appended claims.

Having thus described my invention, what I claim as new and desire to secure by Letters Patent is:

45 1. In an apparatus of the class described, a heat mixing and discharge member, a blower means mounted in connection with said heat mixing and discharge member, a furnace mounted in connection with said heat mixing and discharge member, and a plurality of partitions vertically secured within said heat mixing and discharge member.

50 2. In an apparatus of the class described, a heat mixing and discharge member, a blower means mounted in connection with said heat mixing and discharge member, a furnace mounted in connection with said heat mixing and discharge member, a plurality of partitions vertically secured within said heat mixing and discharge member dividing said heat mixing and discharge member into a plurality of conduits, every alternate conduit thus formed communicating directly with the said furnace and the remainder serving as conduits for air from said blower.

55 3. In an apparatus of the class described, a heat mixing and discharge member, a blower means mounted in connection with said heat mixing and discharge member, an oil burning furnace mounted in connection with said heat mixing and discharge member, and a plurality of partitions vertically secured within said heat mixing and discharge member and extending less than the full length thereof, the ends thereof terminating substantially short of the dis-

charge end of said heat mixing and discharge member.

4. In an apparatus of the class described, a heat mixing and discharge member, a blower means mounted in connection with said heat mixing and discharge member, an oil burning furnace mounted in connection with said heat mixing and discharge member, a plurality of partitions vertically secured within said heat mixing and discharge member and extending less than the full length thereof, the ends thereof terminating substantially short of the discharge end of said heat mixing and discharge member dividing said heat mixing and discharge member into a plurality of conduits, every alternate conduit thus formed communicating directly with the said furnace, and the remainder serving as conduits for air from said blower.

5. In an apparatus of the class described, a heat mixing and discharge member, a blower means mounted in connection with said heat mixing and discharge member, a furnace mounted in connection with said heat mixing and discharge member, a plurality of partitions vertically secured within said heat mixing and discharge member and extending less than the full length thereof, the ends thereof terminating substantially short of the discharge end of said heat mixing and discharge member dividing said heat mixing and discharge member into a plurality of conduits, every alternate conduit thus formed communicating directly with the said furnace, and the remainder serving as conduits for air from said blower, and a pair of shutter members, one positioned on each side of said heat mixing and discharge member near the discharge end thereof so as to permit the heat to be discharged from said heat mixing and discharge member transversely when said shutter members are open.

6. In a mobile orchard heating apparatus, a heat mixing and discharge member mounted thereon with its exhaust end at the rear of said apparatus and below the level of its intake end, a furnace mounted beneath said heat mixing and discharge member near its forward end, and communicating therewith, and a blower means positioned at the forward end of said heat mixing and discharge member and exhausting thereinto.

7. In a mobile orchard heating apparatus, a heat mixing and discharge member mounted thereon with its exhaust end at the rear of said apparatus and below the level of its intake end, a furnace mounted beneath said heat mixing and discharge member near its forward end, and communicating therewith, a blower means positioned at the forward end of said heat mixing and discharge member and exhausting thereinto, and a plurality of conduits positioned within said heat mixing and discharge member and communicating with said burner.

8. In a mobile orchard heating apparatus, a heat mixing and discharge member mounted thereon with its exhaust end at the rear of said apparatus and below the level of its intake end, and a furnace member mounted on the top side of said heat mixing and discharge member and midway between its forward and its discharge ends.

9. In a mobile orchard heating apparatus, a heat mixing and discharge member mounted thereon with its exhaust end at the rear of said apparatus and below the level of its intake end, a furnace member mounted on the top side of said heat mixing and discharge member and midway between its forward and its discharge ends.

ends, and a blower means in connection with the forward end of said heat mixing and discharge member.

- 5 10. In a mobile orchard heating apparatus, a heat mixing and discharge member mounted thereon with its exhaust end at the rear of said apparatus and below the level of its intake end, a furnace member mounted on the top side of said heat mixing and discharge member and midway between its forward and its discharge ends, a blower means in connection with the forward end of said heat mixing and discharge member, and a plurality of conduits positioned within said heat mixing and discharge member and communicating with said furnace member.
- 10 15. 11. In a mobile orchard heating apparatus, a frame member, a heat mixing and discharge member mounted thereon, an oil burning furnace member mounted in connection with said heat mixing and discharge member, a blower means in connection with said heat mixing and
- 20

discharge member to furnish a draft therethrough, and a pair of deflector members positioned at the middle within said heat mixing and discharge member near its exhaust end to deflect heat out to the sides of said apparatus.

- 5 10 15. 12. In a mobile orchard heating apparatus, a frame member, a heat mixing and discharge member mounted thereon, an oil burning furnace member mounted in connection with said heat mixing and discharge member, a blower means in connection with said heat mixing and discharge member to furnish a draft therethrough, a pair of deflector members positioned at the middle within said heat mixing and discharge member near its exhaust end to deflect heat out to the sides of said apparatus, and a pair of shutter members, one positioned on each side of said heat mixing and discharge member near its end to control the discharge of heat from said heat mixing and discharge member.

20 RAY H. TABER.
